UNITED STATES PATENT OFFICE.

WILLIAM H. ENDERS, OF SACRAMENTO, CALIFORNIA.

STARTER FOR EXPLOSIVE-ENGINES.

1,127,212.

Specification of Letters Patent.

Patented Feb. 2, 1915.

Application filed January 12, 1914. Serial No. 811,698.

To all whom it may concern:

Be it known that I, WILLIAM H. ENDERS, a citizen of the United States, residing at Sacramento, in the county of Sacramento and State of California, have invented certain new and useful Improvements in Starters for Explosive-Engines; and I do declare the following to be a full, clear, and exact description of the invention, such as will 5 enable others skilled in the art to which it appertains to make and use the same.

This invention relates to improvements in starting devices for explosive engines and is more particularly designed for use in connection with automobile motors.

The primary object of the invention is to provide a starter of the character described which will exert a continuous movement upon the engine shaft until compression 20 within the cylinders becomes active.

A secondary object is to provide a simply constructed and efficient clutch mechanism whereby the cranking shaft may be connected with the drive shaft of the engine.

Still another object is to provide simple means whereby, should the motor back fire, no serious injury will be imparted to the starting device.

With the above objects in view, the invention resides in certain novel features of construction and combination herein described and claimed and shown in the drawings wherein;

Figure 1 is a plan view of a portion of an 35 automobile chassis showing my improved starter applied thereto; Fig. 2 is a vertical section on the line 2—2 of Fig. 1; Fig. 3 is a vertical cross section on the line 3—3 of Fig. 1; Fig. 4 is a detail vertical section on 40 the line 4—4 of Fig. 1; and Fig. 5 is an elevation of the pawl and ratchet mechanism showing the same disassembled.

In the embodiment illustrated in the accompanying drawings, I have shown diagrammatically an automobile chassis 1 comprising the usual longitudinal bars 2, a front cross bar 3 and an intermediate cross bar 4 between the bar 3 and the rear end of the machine.

Secured in the rear of the cross bar 4 and to the inner side of one of the longitudinal

bars 2, is an inwardly projecting journal shaft 5 the inner end of which is supported in a bearing yoke 6, the ends of which are bolted to the bar 2. Revolubly mounted 55 upon the shaft 5 are outer and inner sprocket wheels 7 and 8 respectively, said sprocket wheels being recessed on their opposing faces and provided with oppositely pitched ratchet teeth 9 and 10 with which 60 oppositely facing dogs 11 and 12, pivoted at the lower end to a lever 13 are adapted to co-act in a manner to be explained.

The lever 13 comprises a lower section 14 which is journaled around the shaft 5 and 65 an upper section 15 which has a sliding engagement with the section 14. By this construction of the lever, I am enabled to lengthen or shorten the power arm thereof.

Revolubly and slidably mounted within 70 the front cross bar 3, is a cranking shaft 16 which is provided on its inner end with a clutch element 17 and on its outer end with a crank handle 18. A curved bracket 19 is secured to the upper face of the bar 3 and 75 projects upwardly a suitable distance above the shaft 16 and carries a pivot pin 20 on which is pivoted the upper end of a curved lever 21 which depends therefrom, has an eye 22 surrounding the shaft 16 and then 80 projects still farther downwardly for a purpose to appear. A sprocket wheel 23 is loosely mounted upon the shaft 16 between the eye 22 and the cross bar 3, said wheel being connected to the shaft by means of a 85 fragile pin 24 which passes through its hub and through said shaft. In order to maintain the shaft 16 and the clutch member 17 in a normally retracted position, I provide a light coil spring 25 between the bar 3 and 90 the gear 23. I also dispose a rather heavy coil spring 26 between the hub of said sprocket wheel and the eye 22 on the lever 21. This last mentioned spring comes into action in a manner which will be more 95 clearly explained.

In order to transmit motion from the sprocket wheels 7 and 8 to the sprocket wheel 23, I provide an endless chain 27 which is looped around a guide pulley 28 100 which is adjustably mounted on a bracket 29 extending rearwardly from the cross bar

4, said chain extending rearwardly from said sprocket 28 and being passed around the rear portions of said sprockets 7 and 8 from which the chain then continues forwardly as most clearly seen in Figs. 1 and 2 and is passed around a guide pulley 30 and a guide sprocket 31 disposed below said pulley, the remaining portion of said chain extending transversely inward from the guides 30 and 31 and being looped around said sprocket 23. By so mounting the chain 27, it will be seen that rotation of the sprocket wheels 7 and 8 upon a transverse axis may be imparted to the sprocket wheel 23 for rotating the longitudinal cranking shaft 16 to crank the motor M when said shaft 16, the clutch member 17 thereon, and the sprocket wheel 23 are shifted as a single unit by means to be described.

20 As above stated, the guide sprocket is adjustably mounted upon the bracket 29 and as clearly shown in the drawings, this adjustment is secured by slotting the end of the bracket 29 as at 34 and passing the journal bolt 35 of the sprocket 28 through this slot and threading a nut thereon. By this feature of construction, I am enabled to compensate for any stretching of the chain 27 or if necessary, for the action of heat or 30 cold thereon.

In the operation of the device, the lever 13 is oscillated, this action causing the dogs 11 and 12 to alternately engage the teeth on the sprocket wheels 7 and 8 and thus drive 35 one of said wheels in a clockwise direction upon the forward movement of the lever and drive the other wheel in a counter-clockwise direction when the lever is moved backwardly. This action of the sprocket wheels 40 7 and 8 will cause the chain 27 to travel around its various guides and transmit motion to the sprocket wheel 23 on the shaft 16 which, by this time, has been thrown inwardly by means of a foot lever 36 connected to the lower end of the lever 21 by 45 a cable 37, so that the clutch member 17 engages a radial pin P carried by the end of the drive shaft S of the motor M. Thus it will be seen that as long as the foot lever 50 36 is rocked in the proper direction and the lever 13 is oscillated, the cranking shaft 16 and the drive shaft S will be rotated, it being understood that this action is continued until the compression within the 55 engine cylinders becomes active and operates the pistons to drive the shaft S in the usual manner.

It may here be explained that, the sprocket wheels 7 and 8 drive the portions 60 of the chain, passing thereover in opposite directions, this being necessary in order that the gear 23 may be turned in one direction on account of the fact that the chain must pass on and off of said sprocket 23 in order

to allow this movement and that this movement of the chain, in passing around said sprocket 23, causes one side thereof to move in one direction while the opposite side moves in a reverse direction.

When the foot lever 36 is pushed forwardly, a rearward pull is exerted upon the cable 37 which motion is transmitted to the lower end of the lever 21. It will thus be clear that said lever will be rocked around the pivot pin 20 and will, through the action of the spring 26, force the gear 23, the shaft 16 and the clutch member inwardly. This movement compresses the spring 25 which does not become active until pressure is released from the lever 36 whereupon it returns the above mentioned parts to their normal positions.

With the parts operating and cranking the motor, should said motor back fire, the fragile pin 24 (the only connection between the sprocket wheel 23 and the shaft 16) will be broken. Thus the remaining parts of the starting device will remain uninjured and a new pin may quickly and easily be substituted for the one broken. This I consider a very important feature of my invention since it obviates the danger of back fire now prevalent with devices of this character.

Having thus described my invention, what I claim as new and desire to secure by Letters-Patent is:—

1. A device of the character described comprising a shaft, sprocket wheels revolvably mounted thereon, internally toothed rings on said wheels, the teeth thereof being oppositely pitched, a lever journaled on said shaft and having oppositely facing dogs in engagement with said teeth, chain guides, a cranking shaft, a sprocket wheel thereon, and an endless chain passing around said guides and said first and second mentioned sprocket wheels for the purpose set forth.

2. A device of the character described comprising a pair of revolvably mounted sprocket wheels, a guide adjustable toward or from the same, a lever, co-acting means on said lever and said wheels for independently rotating said wheels in reverse directions, a slidably mounted engine cranking shaft, an engine shaft, coacting clutch elements on said shafts, a sprocket wheel fixed on said cranking shaft, an endless chain passing around said first and second mentioned sprocket wheels and said guide, and means for projecting and retracting said cranking shaft for the purpose set forth.

3. A device of the character described comprising a bearing, a cranking shaft slideable therein, a clutch element on said shaft, a sprocket wheel secured to said shaft, a light coil spring between said wheel and said bearing, a fixed bracket, a lever pivoted

thereto and having an eye surrounding said cranking shaft, a heavy coil spring between said eye and said sprocket wheel, means connected to said lever for projecting said shaft and said clutch element, an endless chain passing around said sprocket wheel, and means for driving said chain.

In testimony whereof I have hereunto set my hand in presence of two subscribing witnesses.
